UNITED STATES PATENT OFFICE.

ANTHONY L. LEWIS, OF EVANSTON, ILLINOIS.

WINDOW-CLEANER.

SPECIFICATION forming part of Letters Patent No. 483,359, dated September 27, 1892.

Application filed September 4, 1891. Serial No. 404,787. (No model.)

To all whom it may concern:

Be it known that I, ANTHONY L. LEWIS, a citizen of the United States, residing at Evans-
ton, in the county of Cook and State of Illino-
is, have invented certain new and useful
5 Improvements in Window-Cleaners, of which
the following is a specification, reference be-
ing had to the accompanying drawings, which
are made a part hereof, and in which—

10 Figures 1 and 2 are elevations of the im-
proved cleaner viewed from the bottom and
top, respectively. Figs. 3 and 4 are respect-
ively a transverse section and an end eleva-
tion thereof. Fig. 5 is a transverse section of
15 a modification thereof.

The present invention relates to window-
cleaners having a flexible reservoir that will
carry a supply of water sufficient for washing
20 a number of windows and a scraper of custo-
mary construction so arranged that by going
over the window with the working side of the
reservoir it will be thoroughly wet, and by
again going over it with the scraper the water
25 will be removed.

25 The object of my present invention is to
improve window-cleaners of this class; and to
this end my invention consists in certain fea-
tures of novelty that are particularly pointed
out in the claims hereinafter.

30 Referring to the drawings, A represents the
handle; B, the body, (preferably a block of
wood;) C, the scraper, and D the reservoir
for containing the water. In the preferred
35 form of the invention, Figs. 1 to 4, the reser-
voir is molded of soft rubber, the ends D' be-
ing integral with the sides, and it is open at
one side only for the reception of the body-
block B, to the edges of which it is tacked or
otherwise suitably secured. Its walls are
40 thin, so as to be flexible, and its rounded
working surface is provided with a number
of minute perforations d and longitudinal
ribs or corrugations d'. These ribs are desir-
able, because they save the reservoir from a
45 great deal of wear that it would otherwise be
subjected to and because they more effectu-
ally remove the dirt than a smooth surface
could. The scraper C is integral with the res-
ervoir, the two being united by a short flange

or offset c, that rests against the top of the 50
body-block, and may, if desired, be secured
thereto. Within the reservoir there is a
quantity of sponge E or other bibulous mate-
rial that will hold the water by capillary at-
traction and give it up only as fast as it is 55
forced to by pressure.

To use the cleaner thus constructed, it is
immersed in water and allowed to remain un-
til the sponge has by capillary attraction
drawn in through the openings d sufficient wa- 60
ter to thoroughly saturate it. The working
surface of the reservoir is then placed against
and moved over the surface of the glass to be
cleaned, sufficient pressure being exerted to
compress the walls of the reservoir and ex- 65
press from the sponge and through the per-
forations enough water to thoroughly wet the
entire surface. When the glass has been
completely gone over in this way and the dirt
thoroughly softened and loosened, the scraper 70
C is used in customary manner for removing
the dirt and water.

The ribs d' may be omitted.

The scraper C may be separate and attached
to the block independently of the reservoir, 75
as shown by Fig. 5.

Having thus described my invention, the
following is what I claim as new therein and
desire to secure by Letters Patent:

1. A window-cleaner having a handle, a 80
body, a flexible reservoir of impervious mate-
rial secured thereto and having its working
surface perforated, and a mass of bibulous
material within said reservoir, substantially
as set forth.

2. A window-cleaner having the handle A,
the rigid body B, the india-rubber reservoir
D, secured thereto and having the longitudinal
ribs on its working surface, and having, also,
perforations between said ribs, the bibulous 90
material E within said reservoir, and the
scraper C, said scraper and reservoir being
attached to said body, substantially as set
forth.

ANTHONY L. LEWIS.
